Fig. 3

Fig. 1 is a plan view of a puffed textile fabric, showing my new design;

Fig. 2 is a sectional view of the fabric along the line 2—2; and

Fig. 3 is another sectional view of the fabric along the line 3—3.

The design is embodied in a puffed textile fabric having a surface of valleys and raised puffs arranged as shown in Fig. 1. Interlaced threads in the fabric, represented by the straight, horizontal line in Fig. 2, hold the puffs raised.

I claim:

The ornamental design for a puffed textile fabric, as shown and described.
